CLAIM

The ornamental design for a cooling vest, as shown and described.

DESCRIPTION

FIG. 1 is a front, perspective view of a cooling vest in a flat condition showing my new design;

FIG. 2 is a back, perspective view of the cooling vest of FIG. 1; and,

FIG. 3 is a perspective view of the cooling vest shown in a closed position in an enlarged condition upon soaking in water as instructed for use.

The broken lines on the straps and garment in the drawing are understood to represent stitching.
